UNITED STATES PATENT OFFICE.

SYLVESTER F. GEIGER, OF LAKE GENEVA, WISCONSIN.

FOLDING CRATE.

1,274,531.

Specification of Letters Patent.

Patented Aug. 6, 1918.

Application filed December 9, 1915. Serial No. 65,968.

To all whom it may concern:

Be it known that I, SYLVESTER F. GEIGER, a citizen of the United States, residing at Lake Geneva, in the county of Walworth 5 and State of Wisconsin, have invented certain new and useful Improvements in Folding Crates, of which the following is a specification.

My present invention has relation to certain new and useful improvements in crates and more particularly to a folding crate; and as its primary object it contemplates the provision of a novel device of this character which may be used in shipping eggs, or 10 other perishable material, and to be subsequently returned to the consignor in a knock-down condition, thus not only providing adequate protection for the goods during shipment, but also continual reuse of the 15 crate.

Another object of my invention is to provide an improved crate of the nature set forth above, wherein the several parts may be quickly arranged in a folded position 20 and thus held stationary with respect to each other so as to prevent the rattling of the parts and the disagreeable noise incident thereto.

A further object of the invention is to provide novel means to lock the parts of the crate in a relatively stationary position when in a set-up condition and when in a knock-down condition; in the first instance, to provide for adequately protecting the 25 goods during shipment and effectually preventing the collapse of the crate, and, in the second instance, to enable the knock-down crates to be handled with ease.

A further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended 55 claims.

In the accompanying drawings wherein

like characters designate like parts throughout the several views:

Figure 1 is a view in top plan of the 60 crate showing the same in a set-up position;

Fig. 2 is a view in side elevation showing the crate in a set-up position;

Fig. 3 is a reduced view in top plan showing the crate as it appears in a knock-down condition;

Fig. 4 is a longitudinal sectional view 65 taken on line 4—4 of Fig. 1, viewed in the direction indicated by the arrows;

Fig. 5 is a cross sectional view taken on line 5—5 of Fig. 1; and,

Fig. 6 is a sectional view showing the 70 crate in a partly knock-down position.

My improved crate is preferably constructed of a light sheet metal, firstly, to embody the necessary requisites of durability, and secondly to provide for the continual reuse of the device. However, it will be understood that I do not wish to limit myself to this form of material since the crate may be constructed of some other 75 material, if it is so desired.

In reducing my invention to practice, I first provide a base or bottom plate 10, which is bent at its marginal edges to provide upstanding side and end extensions 11 85 and 12 respectively, the end extensions 12 having projecting ears 13 to be secured to the side extensions 11 as shown at 14 in Fig. 2. Suitable bearings 15 are fixed to the side extensions 11 throughout their longitudinal extent, as shown at 16, through which are journaled carrying members 17 and 18 respectively. These carrying members or pivots may be made to extend approximately the entire length of the side extensions, although this is not essential to 90 the efficient operation of the device.

The side pieces 19 may be formed of a light sheet metal, such as pointed out above and may be bent about their marginal edges 100 to provide reinforcing strips 20 and 21 respectively. The side portions are in turn provided with depending brackets 22 which are designed to receive the carrying members 17 and 18, such as shown in Figs. 2 and 105 4, whereby they will be held in pivotal relation with respect to the base or bottom member 10. In the present embodiment, the side members 19 are of a length and width whereby they may be readily accommodated between the side and end extensions 110 of the bottom member and therefore, it will

be noted that they may be quickly arranged in a knock-down position, such as shown in Fig. 6.

The end wall members 23 are bent at their upper and lower marginal edges to form reinforcing strips 24 while at their side edges they are bent to form angular extensions 25 that carry depending ears 26 for attachment to the side extensions 11 of the bottom member as shown at 27. Consequently, it will be also noted that the end members will be held in pivotal relation with respect to the bottom member whereby they may be quickly moved into a knock down position when it is so desired.

With a view of retaining the side and end members in a relatively fixed position with respect to each other when they are in a set-up position, as shown in Fig. 2, I provide the extension 25 of the end members with resilient holding arms 28 whose free ends are bent to form lugs 29 to be received at certain times by the cut outs or recesses 30 of the side members. Consequently, it will be noted that when the side and end members are in the position shown in Fig. 2, they will be held relatively rigid with respect to each other and thus retained against accidental collapse. While these holding arms 28 serve to retain the end and side members in a relatively rigid position, such as mentioned above, attention is also called to the fact that they perform a dual function such as will be hereinafter more fully pointed out.

A carrying member 31 is arranged to extend transversely with respect to the bottom member 10 such as by journaling the ends thereof to the side extensions 11, (see Fig. 5), the purpose of this member being to support a partition member 32. The partition member 32, in its present embodiment, has its marginal edges bent to form reinforcing strips 33, the lower of which is provided with suitable brackets 34 for connection with the carrying member 31. It will be noted from the above that the partition member is readily movable with respect to the bottom portion whereby it may be quickly interchanged from a knock-down to a set-up position. With a view of retaining the partition member in a substantially upright position at certain times, I provide the side members 19 with inwardly projecting stopping lugs 35 (see Fig. 5), between which the partition member may be quickly arranged. Along its upper edge, the partition member is provided with spaced cut outs 36 which serve the function presently described.

In order to effectually close the top of the crate, I provide a cover member 37, which is provided with members 38 (secured thereto at opposite sides) which carry hasps 39 through the medium of pintles 40. The hasps 39 above referred to are designed to

engage, respectively, with the retaining member 41 and the shackle 42 at certain times, such as indicated in Fig. 5, whereby the cover member may be effectually locked in a stationary position.

When the end and side members 19 and 23 respectively are arranged in a set-up position, the side members will be effectually retained against collapse through the medium of the projecting lugs 43 carried by the end members; while the end members are effectually retained with respect to the side members, through the medium of the holding arms 28. The side members 19 are further provided with pivoted arms 44 which are formed with depending lugs or flanges 45 at their free ends for insertion in the cut outs or recesses 36 of the partition member at certain times, whereby the latter will be further held against displacement. The arms 44 not only serve to retain the partition member against displacement, such as mentioned above, but also prevent spreading movement of the side members 19 under strain of the contents of the crate, so as to eliminate bulging of the sides. These securing members 44 also serve as seats for supporting the cover or lid 37 in its operative position.

I also find it expedient to provide each of the several elements of the device with cut out portions or apertures whereby they may receive certain projecting portions of the other elements when they are in a knock-down condition. In the folding operation of the crate (the cover being removed), the side wall members 19 are first manipulated so as to release their engagement with the partition member 32 and allow the latter to be arranged in the position shown in Fig. 6; after which, the side wall members are released from engagement with the end wall members, and may be folded so that the aperture 46 of one side wall member receives the retaining lugs 35 of the other side wall member, while the aperture 47 of the last mentioned side wall member receives the fastening member 42 of the first mentioned side wall member. Consequently, it will be seen that the side members may be arranged in an approximately flat and parallel position. After this has been accomplished, the cover member 37 is arranged in place upon the side members, so that the cut outs or apertures 48 and 49 thereof receive the projecting fastening member 41 of the side portion. The end pieces may now be moved into a folded position whereby the stopping lugs 43 thereof will be received in the cut outs or apertures 50 of the top member whereas the holding arms 28 will be arranged so that the lugs 29 will engage with the bottom of the crate so as to retain the parts in a relatively stationary position. It will be seen that the end members may be thus securely clamped

and bound upon the several folding elements of the crate whereby the entire device will be held in a compact form.

From the foregoing, it will be recognized that I have provided an improved crate which is readily convertible from a set-up position to a knock-down form, one which will adequately protect the goods during shipment and at the same time permit continual reuse, and one which will be materially reduced in size when in a knock down condition. By reason of the fact that it is believed that the advantages and novel features of my invention will be readily understood from the foregoing, further detail description is deemed unnecessary.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. In a folding crate of the character described a base, side and end members movably associated with said base, a cover associated with said side and end members, means to retain said side and end members in an upright position with respect to said base, a partition movably associated with said base and having its upper edge portion provided with cutouts, and latching members pivotally mounted on said side members and having their free end portions movable into the cutouts of said partition to retain the side members against outward bulging, said latching members also supporting said cover while the latter holds the latching members in engagement with said partition.
2. In a folding crate, the combination of a base having side and end walls, the end walls being provided with extensions forming ears connected with the end portions of the side walls, end members for said crate provided with side flanges terminating in ears pivotally connected with the ears of the end walls of said base, side members pivotally connected with the side walls of the base and fitting between the side flanges of the end members when in a set-up position and provided with cutouts adjacent their ends, and strips carried by and extending from said flanges of the end members and terminating in hooks fitting into the cutouts of the side members to releasably hold the end members in engagement with the side members.

3. In a folding crate, the combination of a base having side and end walls, the end walls being provided with extensions forming ears connected with the end portions of the side walls, end members for said crate provided with side flanges terminating in ears pivotally connected with the ears of the end walls of said base, side members pivotally connected with the side walls of the base and fitting between the side flanges of the end members when in a set-up position and provided with cutouts adjacent their ends, strips carried by and extending from said flanges of the end members and terminating in hooks fitting into the cutouts of the side members to releasably hold the end members in engagement with the side members, a partition pivotally connected with the base, securing members carried by the side members for engaging the partition and releasably holding the partition in a raised position, means connecting the side members with the partition to hold the side members against outward bulging, a cover for said crate, and means coöperative with said side members and cover for holding said securing members in engagement with said partition.

In testimony whereof I affix my signature in presence of two witnesses.

SYLVESTER F. GEIGER.
